DESIGN FOR AN AUTOMATIC TOASTER

Abe O. Samuels, Rochester, N. Y., assignor to
Samson-United Corporation, Rochester, N. Y.

Application November 26, 1934, Serial No. 54,165

Term of patent 14 years

To all whom it may concern:

Be it known that I, Abe O. Samuels, a citizen of the United States, residing at Rochester, in the county of Monroe and State of New York, have invented a new, original, and ornamental Design for an Automatic Toaster, of which the following is a specification, reference being had to the accompanying drawing, forming a part thereof.

Figure 1 is a perspective view of the automatic toaster.

Figure 2 is a top plan view showing my new design.

Figure 3 is a rear elevation showing my new design.

The dominant feature of this design resides in the portions shown in full lines.

I claim:

The ornamental design for an automatic toaster, as shown and described.

ABE O. SAMUELS.
